STOKER

John Mason Pilcher, State College, and Frank F. Dennis, Philadelphia, Pa., assignors to Pennsylvania Bituminous Coal Research, Inc., Altoona, Pa., a corporation of Pennsylvania

Application April 19, 1944, Serial No. 531,824

7 Claims. (Cl. 110—45)

This invention relates to stokers, more particularly to underfeed stokers which operate on the principle of partial oxidation of coal prior to its undergoing active combustion.

Underfeed stokers as ordinarily constructed do not operate satisfactorily with strongly coking coals, such as the Pennsylvania coking coals. That is, when it is attempted to burn a strongly coking coal in an underfeed stoker of customary construction there is a strong tendency for unburned coke to be formed and to accumulate and build up above the retort in a generally columnar form known as a coke tree. Coke trees burn primarily at the base, they result in unsatisfactory combustion, especially when the demand on the heating unit is not great, they slow down the response of the furnace to demand for heat and cause over-shooting of thermostatic control, and they make it difficult to maintain low hold-fire rates without danger of the fire going out. In fact, coke tree formation may become so extensive as actually to extinguish the fire or to push open the furnace door.

A method of and apparatus for avoiding the formation of coke trees from coking coals by mildly oxidizing the coal before active combustion begins are described and claimed in an application filed by Theodore S. Spicer and Calvert C. Wright on April 15, 1941, Serial No. 388,626. More in detail, as the coal moves upwardly into and through the lower end of the retort of the stoker it is heated by conduction of heat downwardly from the actively burning coal and in that portion of the column of coal in which the coal is heated but is not yet plastic, i. e., where coking has not begun, the coal is oxidized to an extent such as to reduce but not destroy its coking power. This oxidation is chiefly a surface phenomenon but does not involve active combustion. This is accomplished by introducing an oxidizing agent, most suitably air or an air-stream mixture, into the coal at a point or in a region such that it comes into intimate contact with the heated but non-plastic coal. For brevity this procedure is referred to as a preoxidation method of operating a stoker, or as the preoxidation principle.

Extended experience has demonstrated amply that the preoxidation method easily and satisfactorily represses coke tree formation provided certain critical details are observed. In the first place, the coal must be mixed intimately with the oxidizing agent as it moves upwardly through the preoxidation zone. Second, as the coal is mixed and elevated any substantial segregation must be avoided, i. e., it is necessary to maintain sub-

stantial uniformity of coal size distribution across the section while mixing all of the coal intimately with the oxidizing agent. These features result in subjecting all of the coal uniformly to the action of the preoxidizing air or other oxidizing agent but observance of them is necessary because it has been found that coke tree suppression is not attained satisfactorily if the coal is not thoroughly mixed with the air or if the air distribution is not uniform due to channeling or segregation of the coal into regions containing largely fines and regions containing largely coarse particles. And as indicated above, the coal must be heated but not sufficiently to render it plastic, and enough oxidizing agent must be supplied to produce the desired oxidation before coking of the coal begins.

Although the necessary elevation and mixing of the coal without segregation in the preoxidation zone may be accomplished satisfactorily in various ways, the simplest and most effective means for doing so is a vertical screw. Likewise, although the oxidizing agent might be introduced into the coal at any point prior to the preoxidation zone, it is preferred to supply the oxidizing agent through a supplementary, or preoxidizing tuyère situated below the regular or active combustion tuyères at a distance such that the agent enters the coal substantially at the lower end of the preoxidation zone.

It has been found in actual practice that in the operation of such a stoker there is a tendency for coal to enter the supplementary tuyère, even to the extent of closing the tuyère opening. This is serious because it decreases the amount of air supplied by the supplementary tuyère to the coal and coke trees result because the coal is not oxidized sufficiently. Moreover, continued operation may completely fill the tuyère openings and by forcing coal through the supplementary tuyère cause the wind box to be filled with riddlings, which is objectionable.

Means for alleviating the problem of riddlings in the supplementary tuyère are disclosed and claimed in a copending application, Serial No. 509,071, filed November 5, 1943, by Speer W. Guthrie, now Patent No. 2,366,783, dated January 9, 1945. In accordance with that invention the supplementary tuyère is constructed to have a continuously unobstructed opening for rotation therein of a scraper member which acts to clear coal riddlings from the opening. The embodiment shown includes a vertical screw as the preferred coal elevating and agitating means, and a hooked or claw-like scraper blade connected to

the edge of the screw flight at a level such that it moves through, or around, the tuyère opening when the screw is rotating during the on periods of the stoker.

As far as we are aware, the construction shown in that application was the first means to be provided which afforded any relief from the aforementioned difficulty, experience with it having shown that it acts to sweep riddlings from the opening of the supplementary tuyère and thus permits the tuyère to perform its intended function efficiently. However, while it keeps the tuyère open it tends to push some riddlings into the wind box. While not an insuperable obstacle, that tendency is undesirable because it necessitates periodic cleaning of the wind box and, particularly with domestic stokers, stoker builders seek to eliminate such upkeep requirements as far as possible.

A scraper connected to the edge of the screw flight likewise acts at the same time and in the same plane that the horizontal component of the elevating action of the screw is at a maximum, whereas it would be desirable for the scraper action to lag that component in the plane of the tuyère opening. A construction which accomplishes that is disclosed and claimed in another copending application, Serial No. 509,651, filed November 10, 1943, by Calvert C. Wright, now Patent No. 2,362,604, dated November 14, 1944. In accordance with that invention the scraper is connected to the shaft of the vertical screw at a point such that the maximum horizontal component of the thrust of the screw in the plane of the preoxidation tuyère leads the scraper, suitably by about one-fourth turn of the screw, and preferably the scraper is connected to the shaft closely adjacent the underside of the flight. This construction performs more efficiently than the embodiment shown in the aforesaid application of S. W. Guthrie, but it, too, is open to drawbacks. Thus, the scraper is rigidly connected to the screw shaft and binding of the scraper may occur because of its inflexibility when it encounters a firmly lodged piece of coal, or if a substantial amount of riddlings piles up and packs forwardly of the scraper. Likewise, the claw-like form of the leading edge of the scraper blade tends to push some portion of the riddlings into the wind box, as described above.

The major object of the present invention is to provide a preoxidation type stoker with simple, inexpensive and reliable means for automatically keeping the supplementary, or preoxidation, tuyère free from riddlings, and which not only does so more effectively than the means proposed heretofore, but also eliminates the tendency of those means to push a portion of the riddlings into the wind box.

A further object is to provide a scraper for clearing riddlings from the preoxidation tuyère of a preoxidation type stoker which in simple fashion avoids binding of the scraper.

Yet another object is to provide a scraper blade which is so constructed that coal contacting it in the retort, immediately inside of the tuyère, passes easily over the blade instead of being pushed ahead.

Still another object is to provide a scraper of the foregoing type and for attainment of the foregoing objects which effectively avoids pushing of riddlings into the wind box.

Other objects will appear from the following description.

The invention will be described in detail with

reference to the accompanying drawing in which Fig. 1 is a vertical sectional view through the significant part of a preoxidation type stoker constructed in accordance with one embodiment of the present invention; Fig. 2 a horizontal section taken on line II—II, Fig. 1; Fig. 3 a plan view of the preferred type of scraper; and Fig. 4 a perspective view of one of the scraper blades shown in Fig. 3.

The present invention is predicated upon our discovery that the operation of scrapers mounted in accordance with the principle of the aforesaid application of Calvert C. Wright is improved, while retaining the advantages of that invention, by mounting them for freedom of movement upwardly and downwardly in and laterally of the preoxidation tuyère. In that way binding and related interference due to lodgment of large pieces of coal is avoided.

A further important feature of the invention is the provision of a scraper whose leading edge is designed so that the thrust exerted by it is directed substantially entirely inwardly, i. e., toward the retort, whereby there is no tendency for the scraper to push coal into the wind box.

Through combining both of these features we satisfactorily accomplish cleaning of the supplementary tuyère so that there is no interference with preoxidation to avoid coke tree formation.

Having reference now to Figs. 1 and 2, there is shown a preoxidation type of stoker comprising a retort 1 of conventional form provided with one or more main combustion tuyères which form the active combustion zone in the manner customary in the art. In the embodiment shown there are two such tuyères, 2 and 3, Fig. 1. The retort is surrounded by a wind box 4 supplied with air or other oxidizing agent from a main air duct 5 in any suitable manner, as by a motor driven blower. Coal is introduced to the retort by a horizontal screw 6 operating in a conduit 7. The blower which supplies air to main duct 5 and the screw conveyor 6 are operated in any suitable manner; such drive means form no part of this invention and because they are well understood in the art they do not require illustration or further description.

Coal is delivered by screw conveyor 6 to the bottom of the retort where it is picked up and moved upwardly by a vertical screw flight 8 mounted on a vertical shaft 8a operated by a gear 9 and a pinion 10 which may suitably be driven by the motor which operates screw 6. During the on periods of the stoker screw conveyor 8 moves the coal progressively and continuously upwardly through the retort into the active combustion zone and in so doing the coal is mixed without segregation of particles or pieces of varying sizes.

Disposed in wind box 4 is a partition 11 which divides it into an upper air chamber 12 through which air is supplied to the main combustion tuyères 2 and 3, and a lower air chamber 13 through which air is supplied to the preoxidation tuyère 14. Chambers 12 and 13 act as conduits for supplying air to the main and supplementary tuyères, respectively. Mounted at the juncture of wind box 4 and the main air duct for pivotal movement about the end of partition 11 is a butterfly valve 15. By moving it appropriately, as indicated by the broken line positions, Fig. 1, the air supplied through duct 5 may be apportioned in any desired manner between the upper and lower air chambers 12 and 13. Thus, all of the air may be passed to the upper tuyères 2 and

3, or all of it may be passed to the preoxidation tuyère 14. In ordinary practice, however, valve 15 will be adjusted to supply an amount of air to tuyère 14 which effects preoxidation sufficient to prevent coke tree formation, and air necessary for combustion is passed directly to the active combustion zone through upper air chamber 12 and tuyères 2 and 3. A smoke back opening 16 may be provided as shown in Fig. 1 for the usual purpose of preventing back pressure at this point.

The upper, or active combustion, tuyères 2 and 3 are, as will be observed from Fig. 1, of the usual sectional construction which forms a series of spaced openings between webs 2a and 3a. The preoxidation tuyère 14 has, however, a continuously unobstructed opening, as shown in the drawing, to permit a scraper member 17 to enter and to pass completely around the tuyère opening to sweep from it any pieces of coal that may find their way into it.

In accordance with an important feature of the invention, the scraper 17 is carried by shaft 8a for movement laterally of and vertically in the tuyère 14. To this end the arm 18 which carries the scraper is mounted loosely in the shaft in such manner that the scraper is free to tilt upwardly and downwardly, preferably over a total distance not greater than the height of opening 14, and so that it may move inwardly and outwardly with respect to the opening, this lateral movement being restricted so that at least the tip of the scraper always remains in the tuyère. Although this may be accomplished in various ways, we now prefer to extend arm 18 through shaft 8a and to connect a scraper 17 to each end, as shown in Figs. 1 and 2. The desired freedom of movement is provided by mounting the arm in a bore of sufficiently larger diameter which extends through shaft 8a, while restriction of undue lateral movement is provided for by regulation of the length of arm 17 relative to the scrapers, the sides 14a of tuyère 14 acting as stops to prevent further movement in one direction while a portion of the opposite scraper remains in the tuyère.

The curvature of the leading edges of the scraper 17 shown in Fig. 2 is such that the thrust is preponderantly toward the retort. However, the thrust at the heel of the blade may act to push coal in the retort ahead of the scraper and through the tuyère into the wind box. For that reason we prefer to use scraper blades whose thrust is wholly inward toward the retort. This is accomplished, according to the invention, by so shaping the leading edge, or by so relating it to the supporting arm, that as the shaft 8a rotates the thrust at all points of the blade edge will be toward the retort. Preferably this is done by making the leading edge of the blades 17a straight, instead of curved, and disposing it at an angle relative to the supporting arm 18a, as shown in Fig. 3, in which the arrows from the left hand blade show that the cleaning action is directed solely toward the retort and there is no tendency to push riddlings outwardly, or toward the wind box.

These blades must be relatively thick if they are to keep the tuyère clear, and that portion which moves in the retort may thus act to push coal ahead of it, which is undesirable. We have found, and this is a further important feature of our invention, that that tendency may be reduced or overcome by sloping the portion of the blade that normally moves in the retort upwardly and backwardly from the base of the

leading edge. This is illustrated in Figs. 3 and 4. The scraper blade 17a shown comprises a body having a heel portion 19 for connecting it to arm 18, and the straight leading edge 20 extends from the heel to the tip. This leading edge is, in accordance with preferred practice straight and disposed angularly with respect to the heel so that all of its thrust is inward. A portion of the leading edge adjacent the heel is beveled upwardly and rearwardly from the base as shown at 21 to act as a ramp to allow coal pulled or swept from the tuyère to ride up over and fall behind the blade instead of being pushed ahead of it.

15 The operation of a stoker constructed in accordance with the drawing will be understood from what has been said above. Briefly, during the on periods of the stoker coal from a hopper or bin, not shown, passes through conduit 7 to the bottom of the retort and is there picked up by screw conveyor 8 and moved upwardly toward the active combustion zone. Air for preoxidation enters tuyère 14, which is situated at a point such that the temperature of the coal 20 is sufficient for initiation of the desired preoxidation but insufficient to make it plastic. Under the combined mixing action of conveyor 8, with avoidance of segregation of fines, and of the air introduced through tuyère 14, the coal 25 is sufficiently oxidized by the time it reaches the plastic zone, which lies at or immediately above the upper end of conveyor 8, that coke trees do not form when the coal burns in the active combustion zone, i. e., in the region of tuyères 2 and 3.

30 From what has been said it will be understood, it is believed, how the scraper operates. If coal accumulates in the tuyère 14 to such an extent that it can not be dislodged easily, the 35 scraper automatically adjusts itself to take smaller bites and progressively clears the opening in that way. With the special contouring of the scraper blade the wind box is kept free from riddlings. Hence the preoxidation tuyère acts to perform the desired preoxidation without interference or interruption, and the stoker operates without coke tree formation.

The scraper supporting arm 18 is most suitably carried by the screw shaft according to the 40 preferred embodiment described in the aforesaid application of Calvert C. Wright. That is, the bore which receives the arm is located not far below the flight and at an angular position relative thereto such that the horizontal component 45 of the upward thrust of the flight in the plane of the tuyère leads the scraper, suitably by about one-fourth turn of the flight. In that case it is preferred to operate the screw so that an open area occurs just above and below the scraper arm.

50 Various modifications are, of course, permissible. For example, the scraper member may be connected in other ways than shown in the drawing, and other variations not departing from the gist of the invention will occur to those skilled in the art.

This application together with all of the other applications referred to hereinabove are owned by a common assignee.

55 According to the provisions of the patent statutes, we have explained the construction and mode of operation of our invention and have illustrated and described what we now consider to represent its best embodiment. However, we desire to have it understood that, within the scope

of the appended claims, the invention may be practiced otherwise than as specifically illustrated and described.

We claim:

1. An underfeed stoker comprising the combination of a substantially vertical retort provided with a main combustion tuyère at the upper portion where active combustion occurs, means for supplying coal to the lower end of said retort, a vertical screw disposed in said retort for moving coal upwardly in the retort, the upper end of said screw being disposed below the plane of said tuyère, a supplementary continuously unobstructed tuyère disposed in the retort wall below said main combustion tuyère for supplying air to the coal engaged by said screw in a region where the coal is heated but not plastic, conduits for supplying an oxidizing agent to the said tuyères, and a scraper member extending into said supplementary tuyère and loosely carried by the shaft of said screw for movement relative to said tuyère opening.

2. An underfeed stoker comprising the combination of a substantially vertical retort provided with a main combustion tuyère at the upper portion where active combustion occurs, means for supplying coal to the lower end of said retort, a vertical screw disposed in said retort for moving coal upwardly in the retort, the upper end of said screw being disposed below the plane of said tuyère, a supplementary continuously unobstructed tuyère disposed in the retort wall below said main combustion tuyère for supplying an oxidizing agent to the coal engaged by said vertical screw in a region where the coal is heated but not plastic, conduits for supplying said oxidizing agent to the said tuyères, an arm mounted loosely in a bore through the shaft of said screw and extending from both sides of the shaft, and scraper members connected to the ends of said arm and extending into said supplementary tuyère for keeping it clear of coal.

3. An underfeed stoker comprising the combination of a substantially vertical retort provided with a main combustion tuyère at the upper portion where active combustion occurs, means for supplying coal to the lower end of said retort, a vertical screw disposed in said retort for moving

coal upwardly in the retort, the upper end of said screw being disposed below the plane of said tuyère, a supplementary continuously unobstructed tuyère disposed in the retort wall below said main combustion tuyère for supplying air to the coal engaged by said vertical screw in a region where the coal is heated but not plastic, conduits for supplying air to the said tuyères, and a scraper member extending from within the retort into said supplementary tuyère and loosely mounted in a bore through the shaft of said screw, the portion of said scraper within the retort being beveled upwardly and rearwardly from the base of its leading edge.

15 4. A stoker according to claim 1, said scraper member having a body portion terminating at one end in a heel and having a straight leading edge disposed at an angle to said heel providing scraping thrust in the tuyère opening at said edge substantially wholly inwardly from the tuyère opening toward the retort.

5. A stoker according to claim 2, said scraper member having a body portion terminating at one end in a heel and having a straight leading edge disposed at an angle to said heel providing scraping thrust in the tuyère opening at said edge substantially wholly inwardly from the tuyère opening toward the retort.

25 6. A scraper blade for rotation in a tuyère of a stoker to scrape solid matter from the tuyère into the retort of the stoker, said blade having a body terminating at one end in a heel portion and having a straight leading edge extending along one side at an angle to the heel providing scraping thrust at said edge directed substantially wholly inwardly from the tuyère toward the retort.

30 7. A scraper blade for rotation in a tuyère of a stoker to scrape solid matter from the tuyère into the retort of the stoker, said blade having a body portion integral with a heel portion for connection to a driving member and having a straight leading edge extending along one side at an angle to the heel providing scraping thrust at said edge substantially wholly inwardly from the tuyère toward the retort, and said edge having a portion 40 beveled rearwardly and upwardly from its base.

JOHN MASON PILCHER.
FRANK F. DENNIS.
